UNITED STATES PATENT OFFICE.

CHARLES E. MAGGARD, OF KANSAS CITY, MISSOURI.

EXPANSIBLE MOLD.

1,086,379.

Specification of Letters Patent. Patented Feb. 10, 1914.

Application filed March 27, 1913. Serial No. 757,107.

To all whom it may concern:

Be it known that I, CHARLES E. MAGGARD, a citizen of the United States, residing at Kansas City, in the county of Jackson and 5 State of Missouri, have invented certain new and useful Improvements in Expansible Molds, of which the following is a specification.

This invention relates to expansible cores 10 for concrete work, and particularly to expansible core sections for use in the construction of concrete culverts.

One of the objects of the invention is to produce a simply constructed device of this 15 character, which may be readily expanded for different sizes of culvert arches, and afterward collapsed for removal from the molded structure.

Another object is the provision of means 20 whereby such devices will be made more easily portable when in collapsed form.

With these and other objects in view as will be seen in the course of the description, my invention resides in various details and 25 peculiarities of construction, all as fully illustrated and described in the following specification, taken in connection with the accompanying drawing, in which—

Figure 1, is a top plan view, partly broken 30 away, of the steel frame work of my device fully expanded, and with the shell of cover plates removed; Fig. 2, is a bottom plan view of the main frame of the machine, with a pair of the expanding sections shown fully 35 collapsed; and Fig. 3, is an end elevation of the device in expanded condition and the cover plates applied thereto.

Referring to the drawing, the main frame 40 of the machine is constructed of angle iron bars 2, joined together and spaced a slight distance apart by cross braces 4. Between the opposite ends of these bars and secured thereto are stationary brackets 6 provided with journal bearings for the opposite ends 45 of a shaft 8, the terminals of which are squared at 10, for engagement by a crank 12 at times when the shaft is to be turned.

Mounted upon the shaft 8 is a series of 50 sliding heads 14, 14, and 16, 16, the heads 14, 14, being threaded for engagement by the oppositely threaded portions at the ends of said shaft, while the heads 16, 16, are smooth-bored for free movement upon the plain middle portion of the shaft, and over 55 the threaded portion.

Each of the sliding heads is provided with

a series of radially projecting pivot lugs 18, bored to receive pivot bolts or pins 20 on which to support for pivotal movement the series of arch bars 22. The uppermost and the lowermost of said lugs will each support a pair of such bars, each pair extending to practically the same point of the arch, whereby it will be seen that the extra support is afforded along the middle line of the arch and at the bottom margins of the sides, where additional strengthening is desirable. The outer ends of these arch bars are pivotally joined to a series of angle bars 24 which are for the purpose of supporting the several cover plates 26 that form the outer shell of the core, which plates are folded along their upper edges into hook form for engagement with the bars 24, as shown clearly in Fig. 3. The plates 26 of each side of the arch engage each other slidingly, and are wide enough to maintain over-lapping contact even when the arch is fully expanded. The adjacent edges of the top plates 26 are joined by the same pivotal connections which unite the corresponding bars 24 with the middle bars 22.

In order that the heads 16 will move in unison with the heads 14, each head 16 is connected with the adjacent head 14 by a 55 pair of bars 28.

It will now be understood that as the shaft 8 is turned by means of the crank 12, the heads 14 will be moved either toward or from the ends of the shaft, and will correspondingly move the heads 16, as a result of which the bars 22 and the parts supported thereby will be moved along lines extending radially outward or inward relatively to the shaft. Since the plates overlap and 60 slide upon each other, they readily adapt themselves to the changing positions of the supporting bars, so that by proper manipulation of the crank 12, a shell may be obtained of any desired radius, within the 65 range provided for by the bars 22, which arch bars I contemplate supplying in various lengths so as to give whatever range of adjustment may be required.

Secured beneath each of the brackets 6 is a plate 30, extending transversely of the main frame, and to the under face of each of these plates 30 is bolted a shaft 32 of a length to carry a pair of wheels 34 spaced apart a distance slightly greater than the width of 70 said main frame. Having the apparatus 75 thus mounted on wheels at each end will

greatly facilitate withdrawal of it from the molded culvert, and at the same time avoid subjecting the apparatus to the undue wear from scraping and jarring which arises 5 from dragging it about instead of having it on wheels.

For insuring tight fits between the overlapping plates 26, irrespective of the radius of the mold, a plurality of wires 36 are 10 banded around the mold, the ends of the wires being preferably twisted together at 38 to hold the plates—which are of spring metal,—curved concentrically of the shaft 8; the wires being removed when the mold 15 is collapsed.

From the foregoing it will be apparent that I have produced an expandible core for concrete work possessing the advantageous features enumerated as desirable in the 20 statement of the object of the invention, and I wish it to be understood that while I have illustrated and described one form of the invention, I reserve the right to make such changes as fall within the spirit and scope 25 of the appended claims.

I claim;

1. In an expandible arch for culverts, a central frame, a shaft mounted thereon and provided with threaded end portions, each 30 end portion being oppositely threaded from the other end portion, a pair of heads mounted on each end portion of the shaft and slidably mounted on the frame, one of each pair of heads being threaded to corre-

spond with the adjacent end portion of the 35 shaft and its companion head being bored to move freely over said end portion, links connecting the heads of each pair whereby upon turning of the shaft each pair of heads will move in unison toward or from the 40 other pair of heads, a series of plates forming an arch about said frame as a center, and a series of links connecting said plates to said heads and arranged to move said plates radially with reference to the frame 45 as the heads are moved.

2. In an expandible arch of culverts, a central frame, a series of plates arranged in substantially semi-circular form about said frame as a center, said frame comprising a 50 pair of longitudinal bars connected by cross braces, a pair of supporting wheels carried by each end of the frame in the plane of the base of said arch, a series of oppositely sliding heads mounted on said frame and a 55 series of oppositely swinging links connecting said heads to said plates and arranged to move the latter radially with reference to the frame as the heads are moved, and means carried by said frame for sliding said 60 heads.

In testimony whereof, I affix my signature, in the presence of two witnesses.

CHARLES E. MAGGARD.
